EXHAUST FAN

Melroy Sinclair, 7627 Lindbergh Drive, St. Louis, Mo.
Filed Sept. 25, 1961, Ser. No. 140,607
1 Claim. (Cl. 98—94)

The present invention relates generally to exhaust fans, and more particularly to a novel exhaust fan for disposition in a window for moving air from a room, such as a bathroom, kitchen, or the like.

Many devices have been constructed for changing the air in bathrooms, and other relatively small places. However, in the applicant's experience, none of these has supplied the long-existing need of a simple, inexpensive, readily installable and removable, safe, highly effective device. Householders in particular have long sought something that will exhaust the odors from a bathroom in an efficient manner, and yet neither block the window nor be an objectionable, highly unsightly addition to the room.

Therefore, an object of the present invention is to provide a solution to the long existing problem, namely, an exhaust fan small of size, yet effective in its operation, which can be disposed in a window or removed therefrom in a matter of a minute or two.

In brief, the present novel exhaust fan includes a novel casing, a blower and a motor installed within the casing, a gravity-actuated valve normally closing an air passage, novel means for locating the casing on a window ledge, and means for sealing the casing in a selected position in the window.

Therefore, another object of the present invention is to provide a novel exhaust fan which is particularly adapted for ready disposition in and removal from the window of a bathroom, or the like.

Another object is to provide a novel exhaust fan which is inexpensive and light of weight, so that it can be readily installed in and removed from the window of a bathroom, or the like, by the lady of the house, requiring no tools once the associated burglar lock is installed.

Another object is to provide a novel exhaust fan for bathroom windows, and the like, which incorporates a novel casing including an air discharge chute or passage in which is disposed a simple, gravity-actuated flap valve.

Another object is to provide a novel exhaust fan for bathroom windows, or the like, which is quiet in operation, which can be readily installed in a window, which requires only a small cracking of the window so that forced removal of the fan would not provide an enlargement sufficient for entry, which is highly effective in its exhaust operation, and which otherwise fulfills the objects and advantages as set forth.

The foregoing and other objects and advantages are apparent from the following description, taken with the accompanying drawings, in which:

FIGURE 1 is a side elevational view of a window of a bathroom, or the like, in which is installed in operative position an exhaust fan incorporating the teachings of the present invention, said window being viewed from inside the room;

FIGURE 2 is an enlarged vertical cross-sectional view taken on substantially the line 2—2 of FIGURE 1;

FIGURE 3 is an enlarged vertical cross-sectional view taken on substantially the line 3—3 of FIGURE 1;

FIGURE 4 is a side elevational view of the present novel exhaust fan looking at the side opposite that shown in FIGURE 3, the electric cord being broken away for conservation of space;

FIGURE 5 is a further enlarged substantially horizontal sectional view, illustrating the blower, motor and flap valve in top plan;

2

FIGURE 6 is a vertical cross-sectional view taken on substantially the line 6—6 of FIGURE 5;

FIGURE 7 is a still further enlarged fragmentary cross-sectional view of the air exhaust chute of the casing and the gravity flap valve;

FIGURE 8 is a view similar to FIGURE 7, but with the gravity flap valve omitted;

FIGURE 9 is a view similar to FIGURE 8, but looking at the other side of the air exhaust chute;

FIGURE 10 is a front elevational view of the gravity flap valve; and

FIGURE 11 is an isometric view of a foam stuffer strip used in sealing the window against the passage of air and other weather.

Referring to the drawing more particularly by reference numerals, 15 indicates generally an exhaust fan constructed in accordance with the teachings of the present invention. The exhaust fan 15 includes a novel casing 16 of the configuration clearly shown in the drawings, 15 including a base shell 18 and a side closure 20 removably maintained in position by screws 22. An air discharge chute 24 extending transversely of the exhaust fan 15 is formed at one side of the base shell 18. An external transverse rib 26 is formed on the shell 18 inwardly of the end of the chute 24, as is clear from FIGURE 6. An air intake grill 28 is formed integral with one side of the shell 18.

Formed integral with and extending inwardly of the closure 20 are four spaced internally threaded posts 30 on which is mounted a fractional horsepower motor 32 by means of screws 34. The motor 32 includes a rotor shaft 36, on an extension of which is mounted a cage type blower 38 by means of a hub 40, set screw 42, and end plate 44.

The closure 20 also includes an inwardly directed recess 46 in which is mounted the actuating lever 48 of a toggle switch 50 operatively connected by suitable wires 52 to the motor 32. A cord 54 is also operatively connected into the motor 32 and switch 50, which has a plug 55 for connection to a source of power.

A gravity actuated flap valve 56 is pivotally mounted within the casing 16 at the inner end of the chute 24 by means of integral opposed projections 58 pivotally mounted in opposed wells 60 and 62 in the sides of the shell 18 and the closure 20, respectively (FIGS. 8 and 9). The flap valve 56 is of light weight material, such as aluminum, so that it will assume readily and stay in the position of FIGURE 7 when the blower 38 is in operation. It is to be understood that the flap valve 56 closes the chute 24 when the blower 38 is not in operation, so that cold or hot air from the outside cannot back up through the exhaust fan 15 and into the room.

In FIGURES 1-3, the exhaust fan 15 is shown mounted in the window 64 of a bathroom, or the like. As is clear from FIGURES 1 and 3, the exhaust fan 15 rests upon the sill 66 of the window 64 with the chute 24 extending beneath the bottom of the lower sash 68 thereof. A sealing strip 70 is disposed on and stuck to the top of the chute 24 and is engaged by the bottom of the lower sash 68. A foam stuffer strip 72 closes the space between the bottom of the lower sash 68 and the top of the sill 66. A foam stuffer strip 74 seals the space between the lower sash 68 and the upper sash 76. A conventional burglar-proof latch member 78 is mounted on top of the lower sash 68 in engagement with one side of the upper sash 76 in the usual manner.

The exhaust fan 15 is shown mounted against one side of the window 64, although it can be shifted over to the right at least as far as the window handle 80, if desired. If moved towards the center of the window 64, as sug-

gested, the stuffing 72, would, of course, be disposed on both sides of the exhaust fan 15.

It is manifest from the foregoing description of the drawing that once the burglar lock 78 is installed on the lower sash 68, the exhaust fan 15 can be easily and readily installed or removed, as desired, by the housewife. No screws or other securing means are provided, and the foam or other type stuffer strips 72, 74 are not glued or otherwise secured against removal.

It is also clear that the present novel exhaust fan fulfills the objects and advantages sought therefor, thus satisfying the long-felt need for such a device.

It is to be understood that the foregoing description and the accompanying drawing have been given by way of illustration and example. It is also to be understood that the changes in form of the elements, rearrangement of parts, and substitution of equivalent elements, which will be obvious to those skilled in the art, are contemplated as within the scope of the present invention, being limited only by the claim which follows.

What is claimed is:

In combination, an exhaust fan for windows comprising a casing, a ridge extending downwardly from the bottom of said casing disposed transversely thereof adjacent the inner end of the chute for locating the exhaust fan on a window sill, a motor mounted in said casing, a blower in said casing operatively connected to said motor, said casing including an exhaust chute extending out-

wardly from the base thereof, an air passage beneath said motor and blower communicating with said chute, an opening adjacent said blower for drawing air from the room into said casing, said casing being of a depth and size to rest upon a window sill substantially without extending into the room, a normally closed gravity actuated flap valve in said exhaust chute, said valve being of lightweight material so as to open and remain open when said blower is in operation, said exhaust chute having a substantially horizontal area across the top for disposition beneath the bottom of a lower window sash, and sealing means on said substantially horizontal area for engagement by the bottom of a lower sash, said exhaust fan being maintained in operative position in a window solely by engagement of the lower sash with said sealing means, the engagement of the bottom of the casing with the window sill, and the engagement of the casing rear above the chute with the lower sash.
